A. J. NELSON

NECKTIE HOLDER

Filed Dec. 1, 1921

Patented May 1, 1923.

1,453,885

UNITED STATES PATENT OFFICE.

ANNA J. NELSON, OF NOME, ALASKA.

NECKTIE HOLDER.

Application filed December 1, 1921. Serial No. 519,235.

To all whom it may concern:

Be it known that I, ANNA J. NELSON, a citizen of the United States, residing at Nome, W., Territory of Alaska, have invented certain new and useful Improvements in Necktie Holders; and I do hereby declare the following to be a full, clear, and exact description of the invention, such as will enable others skilled in the art to which it appertains to make and use the same.

This invention relates to an improved necktie holder and is an improvement over that shown in my prior Patent Number 1,242,841 issued October 9th, 1917.

One object of the invention is to provide a necktie holder so constructed that it may be collapsed into a flat mass when not in use, thus permitting it to be stored in a small space and to further so construct the necktie holder that it may be suspended in an extended position when in use.

Another object of the invention is to provide an improved type of necktie engaging clamp which will be simpler in construction than that shown in my prior patent and which will obtain a very firm grip upon the tie and securely hold it in stretched condition.

Another object of the invention is to provide a necktie holder which may be formed almost entirely of lengths of heavy wire or light rod metal.

Another object of the invention is to so construct the necktie holder and stretcher that it will be simple in construction and cheap to produce.

This invention is illustrated in the accompanying drawings wherein—

Figure 1 is a perspective view of the improved necktie holder,

Figure 2 is a transverse sectional view through the necktie holder looking towards the lower end thereof,

Figure 3 is an enlarged fragmentary, sectional view taken on line 3—3 of Figure 1 and looking in the direction of the arrows.

This necktie holder is provided with a rear frame indicated in general by the numeral 10 and a forward frame indicated in general by the numeral 11, the rear frame being provided with side bars 12 and upper and lower cross bars 13 and the forward frame being provided with side bars 14 and with upper and lower bars 15 and 16. The end portions of these bars 11, 12, 13, 14, 15 and 16 are bent to provide eyes through

which extend bolts 17 and since these bolts also extend through eyes formed in the ends of the connecting bars 18 at the upper and lower ends of the rear and forward frame, it will be readily seen that the forward frame may have a swinging movement longitudinally of the rear frame and thus moved from an extended position to a collapsed position with the forward frame fitting against the rear frame. Since the frame 11 is swung upwardly to a collapsed position it will naturally have a tendency to move downwardly and therefore when the necktie holder is lifted and suspended by the brackets 19 mounted upon the securing bolts at the upper ends of the rear frame, the forward frame will have a tendency to drop downwardly to the extended position. In order to prevent the forward frame from dropping beyond the desired position shown in Figure 1, there has been provided an abutment bar 20 which is formed of resilient material and is mounted upon the upper bar 13 of the rear frame. This supporting bar is limited in its downward movement beyond a horizontal position and therefore it will serve to securely support the forward frame in the extended position. The neckties will be hung across the upper bar 15 of the forward frame and brought downwardly and extended in front of the lower bar 16 which bar will have a flat forward face. The clamping bar 21 which is pivotally connected with the lower end portion of one of the side bars 14 of the forward frame will be swung inwardly to engage the ties and hold them in tight engagement with the bar 16.

The tie engaging face of the bar 21 is flat similar to the outer face of the bar 16 and it will thus be seen that the ties may be tightly gripped between the two bars without being damaged. A spring clip 22 is carried by the free end portion of the bar 21 for engaging the bar 14 of the forward frame thus releasably but securely hold the clamping bar in an operative position. There has thus been provided a necktie holder in which the ties may be securely held in a stretched condition and thus wrinkles removed from them. There has further been provided a necktie holder which will remain in an extended position when in use and therefore hold the ties out of engagement with a wall or door from which the holder is suspended and which is so constructed that when not in use the holder may

be collapsed or folded into a compact mass thus permitting it to be stored in a small space. A very convenient and efficient tie holder has therefore been provided.

5. What is claimed is:—

1. A holder comprising a rear frame having side bars and upper and lower bars, a forward frame adapted to swing relatively thereto to and from a collapsed position and 10 having side bars and upper and lower bars, said bars having their end portions formed into eyes, connecting bars extending between the forward and rear frames and having their end portions formed into eyes 15 registering with the eyes of the forward and rear frames, fasteners extending through the registered eyes to pivotally connect the connecting bars with the forward and rear frames whereby the forward frame may 20 have vertical swinging movement, means for limiting the downward swinging movement of the forward frame and means for clamping ties in engagement with the forward frame.
25. 2. A holder and stretcher comprising a rear frame, a forward frame adapted to swing relatively thereto to and from a collapsed position, connecting arms pivotally

connected with the forward and rear frames, a support connected with the rear frame and 30 extending for engagement with the forward frame to limit downward movement of the forward frame, and means for holding ties in engagement with the forward frame.

3. A holder comprising a rear frame, a forward frame, means for connecting the forward frame with the rear frame for movement into and out of an operative position, said forward frame having side bars 40 and upper and lower bars, the upper bar constituting a tie supporting bar, and the lower bar a clamping bar, a second clamping bar pivotally connected with one of the side bars for swinging movement into and out of 45 position in front of the lower bar of the forward frame, and means for releasably connecting the free end portion of the clamping bar in engagement with the second side bar of the forward frame.

In testimony whereof I affix my signature in presence of two witnesses.

ANNA J. NELSON.
